DESIGN FOR A SUIT

Edward Minkoff, New York, N. Y.

Application December 19, 1941, Serial No. 104,743

Term of patent 3½ years

To all whom it may concern:

Be it known that I, Edward Minkoff, a citizen of the United States of America, residing in New York city, county of New York, and State of New York, have invented a new, original, and ornamental Design for a Suit, of which the following is a specification, reference being had to the accompanying drawing, forming part thereof, wherein,

I claim:

The ornamental design for a suit, substantially as shown:

EDWARD MINKOFF.
